TELEVISION ANTENNA

Jack W. Weston, 112 Fir St., Hendersonville, N. C. 28739

Filed Nov. 2, 1967, Ser. No. 9,251

Term of patent 14 years

(Cl. D26—14)

FIG. 1.

FIG. 2

FIGURE 1 is a perspective view of a television antenna, showing my new design, the folded dipole members and the mast member are broken away to indicate indeterminate length.

FIGURE 2 is a perspective view as seen from the opposite side.

I claim:

The ornamental design for a television antenna, as shown and described.
